CARL P. BERGSTROM, OF MILLBURY, MASSACHUSETTS, ASSIGNOR TO CROMPTON & KNOWLES LOOM WORKS, OF WORCESTER, MASSACHUSETTS, A CORPORATION OF MASSACHUSETTS

MOUNTING FOR WEFT DETECTORS

Application filed January 15, 1929. Serial No. 332,693.

This invention relates to improvements in weft detectors more particularly to the means for supporting the same to the end that the detector may move forwardly if engaged by a misplaced bobbin.

In multicolor weft replenishing looms it is customary to locate the weft detector under the magazine. Because of this construction it occasionally happens that a misplaced bobbin may be caught by the lay and moved against the detector. Where the detector is of the side slipping type it is usually capable of sufficient movement either forwardly or laterally to avoid damage either to the bobbin or itself, but it is preferable under some conditions to provide for the forward yielding of a side slipping weft detector. In my co-pending application Ser. No. 263,469, I have shown a means for mounting a weft detector on one of the tie rods of the usual form of stationary magazine. In that application the depending support is held in fixed position on the tie rod.

It is an important object of my present invention to provide yielding means for the support together with guide means so that as the support moves pivotally with respect to the tie rod it will not lose its proper position in a direction longitudinally of the surface being detected.

It is a further object of my invention to provide a detector support and a guide for the mounting adjustable longitudinally and angularly with respect to the tie rod, the support being movable relatively to the guide member against the action of a yielding element which serves to return the detector support to normal position.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a vertical section through a weft replenishing mechanism of the multicolor type showing my improved form of detector applied thereto;

Fig. 2 is an enlarged vertical section on line 2—2 of Fig. 1, and

Fig. 3 is a detailed horizontal section on line 3—3 of Fig. 2.

Referring particularly to Fig. 1, I have shown a loom frame 10 on which is mounted a magazine 11 of the usual multicolor form. Said magazine includes in its construction several tie rods, two of which are shown at 12. The lay 13 is provided with the usual box back 14 and binder 15 between which is received a shuttle S carrying the bobbin B. Aligning slots 16 are provided in the binder and shuttle for the reception of a detector 17.

The detector may be of the form shown in co-pending application, Ser. No. 200,481, filed by Payne, and includes a bed 18 and cap 19 between which slide a carrier the forward upturned end of which is indicated at 20 in Fig. 1. A bolt 21 extends through the bed and cap and also through a horizontal extension 22 of a depending arm 23 which derives its support from the forward tie rod 12.

The matter thus far described relates particularly to the type of magazine shown in Patent No. 1,030,748 and the detector parts may be substantially the same as those shown in the previously mentioned co-pending applications and form no part of my present invention. My invention is not limited in its use to the particular form of detector shown, and it is sufficient for the purposes of my present invention to state that the detector will ordinarily function without movement of the extension 22 or arm 23.

In carrying my present invention into effect I form the upper end of the support 23 with a hub 30 through which freely extends the forward tie rod 12. This hub is free to rotate in a right hand direction as viewed in Fig. 1 about the tie rod except as it is restrained yieldingly by a torsion spring 31 having an end 32 extending as at 33 behind a guiding and holding member 34. The latter is held in adjusted longitudinal and angular position on the forward rod 12 by a set screw 35.

The member 34 is provided with a horizontal arm 36 provided with a notch 37 to re-

ceive the upper portion of the support 23. The notch 37 limits rearward movement of the support 23 under action of the spring 31, the rear end of the notch being determined as to position by the set screw 35.

In operation the lay 13 will have a detecting beat every alternate pick of the loom to present the bobbin B to the detector 17. Under normal conditions the support 23 will 10 remain at rest, the spring 37 being sufficiently strong to overpower the yielding devices not shown which act upon the detector. Should a misplaced bobbin be accidentally interposed between the lay and the detector 13 or the 15 bed and cap, the lower end of the support 23 will move in a clockwise direction as viewed in Fig. 1 around the tie rod 12 against the action of spring 31. The slot 37 is of sufficient depth and is near enough to the 20 axis of the support 23 so that it will be operatively related to the detector carrier for all probable movements of the latter in a forward direction. When the abnormally placed bobbin is removed the spring 31 will 25 act to restore the support 23 to its normal position in the notch 37.

From the foregoing it will be seen that I have provided a very simple means for supporting a weft detector on a usual part of a 30 multicolor weft replenishing loom so that the guiding and positioning member 34 may act to locate the position of the bed and detector in a direction toward and from the lay, while permitting yielding forward movement of the detector. It will further be seen that the arm 36 is so near the tie rod 12 that a portion of the support will occupy 35 the notch 37 for practically all forward positions of the supporting member 23.

40 Having thus described my invention it will be apparent that changes and modifications may be made therein by those skilled in the art without departing from the spirit and scope of the invention and I do not wish to be limited to the details herein disclosed, but 45 what I claim is:

1. In a weft detector for a loom having a surface to be detected, a normally fixed member substantially parallel to the surface to be detected, a support longitudinally and angularly adjustable on the member, a weft engaging detecting element mounted on the support, and a guiding device mounted on the member and held in adjusted angular position 55 on the member and determining the position and path of movement of the support when the latter moves in a direction away from the surface to be detected, and co-operating with the support to limit the movement of the latter along the member in the direction of the length of the latter.

2. In a weft detector for a loom having a surface to be detected, a normally fixed member substantially parallel to the surface to be detected, a yarn engaging weft detect-

ing element, a support for the same supported by the member and movable angularly with respect to the latter in a direction away from the surface to be detected, and a device secured to the member and having portions substantially at right angles to the member along which portions the support may move when the detector moves forwardly, said portions limiting movement of the support longitudinally of the member.

3. In a weft detector for a loom having a surface to be detected, a normally fixed member substantially parallel to the surface to be detected, a yarn engaging weft detecting element, a support therefor movable angularly about the member to carry the detector forwardly, and a guiding device secured to the member and having a pair of spaced portions substantially parallel to the direction of movement of the detector as the latter moves forwardly, said portions being normally in engagement with the support to restrain movement of the latter in a direction parallel to the member.

4. In a weft detector for a loom having a surface to be detected, a normally fixed member substantially parallel to the surface to be detected, a guiding member secured in adjusted angular position on the member and having a slot extending substantially perpendicular to the member, the support extending through the slot and engaging the portions of the guide device on opposite sides of the slot to be restrained as to motion in a direction parallel to the member, and resilient means to hold the support normally seated in the slot, the guiding device positioning the support with respect to the surface to be detected.

5. In a weft detector for a loom having a surface to be detected, a normally fixed member substantially parallel to the surface to be detected, a yarn engaging weft detecting element, a support therefor movable about the member to carry the detector forwardly, a guiding and positioning device secured in adjusted angular position on the member and having a slot to receive the support, said support being movable in a direction substantially perpendicular to the member in one direction and being restrained against movement in the opposite direction by the guiding and positioning device, and resilient means interposed between the device and support to hold the latter normally yieldingly in rearward position against a portion of the device.

6. In a weft detector for a loom having a surface to be detected, a normally fixed member substantially parallel to the surface to be detected, a yarn engaging weft detecting element, a support therefor movable about the member to carry the detector forwardly, and a guiding and positioning device adjustable angularly and longitudinally with respect to the member and having a guide edge

substantially perpendicular to the member to restrain movement of the support in a direction parallel to the member, said support being movable in a direction perpendicular to the member and substantially parallel to said portion.

5 7. In a weft detector for a loom having a surface to be detected, a normally fixed member substantially parallel to the surface to be detected, a yarn engaging weft detecting element, a support therefor movable about the member to carry the detector forwardly, a guiding and positioning device adjustable angularly and longitudinally with respect to the member and having a guide edge substantially perpendicular to the member to restrain movement of the support in a direction parallel to the member, said support being movable in a direction perpendicular to the member and substantially parallel to said portion, and resilient means between the device and the support to hold the latter normally against a portion of the device.

10 8. In a weft detector for a loom having a surface to be detected, a normally fixed member substantially parallel to the surface to be detected, a yarn engaging weft detecting element, a support therefor movable about the member to carry the detector forwardly, a holding and positioning device longitudinally and angularly adjustable on the member, a substantially cylindrical hub formed as a portion of said device, an arm extending below the hub and substantially parallel to the member and having a slot therein to receive a portion of the support, said slot extending in a direction perpendicular to the member, and a torsion spring surrounding the cylindrical hub of the device and engaging the support 15 to hold the latter normally in the slot, said support and detector being movable forwardly against the action of the spring and the support being guided by the portions of the device defining opposite sides of the slot.

20 45 In testimony whereof I have hereunto affixed my signature.

CARL P. BERGSTROM.
